UNITED STATES PATENT OFFICE.

DON PARDEE MOON, OF KOKOMO, INDIANA.

RAZOR-BLADE HOLDER.

Application filed August 22, 1924. Serial No. 733,829.

To all whom it may concern:

Be it known that I, DON PARDEE MOON, a citizen of the United States, residing at Kokomo, in the county of Howard and State 5 of Indiana, have invented certain new and useful Improvements in Razor-Blade Holders; and I do hereby declare the following to be a full, clear, and exact description of the invention, such as will enable others skilled in the art to which it appertains to make and use the same.

The present invention relates to improvements in razor blade holders and has for an object to provide a holder for a blade useful in connection with stropping the blade or forming a knife for ripping seams, sharpening pencils, cutting leather and fur, stencil cutting, wood block carving, whittling, trimming wall paper, erasing ink from drawing paper, paring corns, scraping glass, etc.

Another object of the invention consists in providing an improved device of this character in which a magazine is provided for holding a quantity of the razor blades and in which a novel and improved means is provided for clamping the blade in the holder.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view, partly broken away, showing an improved holder constructed according to the present invention.

Figure 2 is a longitudinal section taken therethrough.

Figure 3 is a cross section taken on the line 3—3 in Figure 1.

Figure 4 is a plan view, partly broken away of a modified form of the invention.

Figure 5 is a longitudinal section therethrough.

Figure 6 is a transverse section taken on the line 6—6 in Figure 4.

Figure 7 is a plan view with parts in section of a still further modified form, and

Figure 8 is a fragmentary section showing a detail.

Referring more particularly to the drawings and for the present to Figures 1 to 3 inclusive, the device consists generally of

two members having the substantially flat clamping jaws 9 and 10 perforated to receive the screw post 11 having the nut 12 threaded thereon for binding the clamp jaws 60 upon the blade indicated at 13. The nut 12 is preferably a wing nut for facility in gripping and turning. The head of the screw post 11 is preferably square to engage a square opening in the jaw 10 to avoid rotation when turning the nut 12; or the head may be secured against rotation in any desired manner.

Back of the jaws the two members are cut away as indicated at 14 and 15, the removed portions being preferably on relatively reverse arcs of circles in order to admit the thumb and finger to accommodate the contour of these members. A neck 16 is left between the removed portions and 70 just forwardly of the removed portions and preferably on the longitudinal centers of the members are perforations 17. As shown in Figure 2 the planes of the clamps 9 and 10 are off set toward one another inwardly of 80 the planes of the remaining portions of the two members.

The outer portions 17 and 18 of the members are preferably longer than the clamps 85 and constitute a handle for supporting the blade holder when in use. The handle members 17 and 18 are closed at their sides as indicated at 19 and 20 in Figure 3 in order to provide a magazine for holding additional blades as shown. The members are secured 90 together by a post or rivet 21 at a point preferably on the longitudinal centers of the members and outwardly of the convergent portions 22 and 23 thereof in order not to interfere with the resilient action of the members.

These members are made of preferably some metal possessing sufficient inherent resiliency to normally hold the clamp jaws 9 and 10 slightly apart and the resilient action is heightened by the convergent parts 95 22 and 23 in combination with the cut out side portions 14 and 15 and the perforations 17. The rivet 21 is placed also with reference to the length of the blades to be accommodated in the magazine. The end of the 100 handle portion is open so that the blades may be inserted within this part and the rivet is spaced from this end portion slightly longer than the greatest length of the blade to be received in the magazine.

Both ends of the 105 handle portion are preferably rounded as indicated in Figure 1 and the open end of the maga- 110

zine may be kept closed by the arcuate cover 24 provided with the indented end portions 25 for engaging the side walls of the magazine when the cover is closed in order to hold it in this position until actively and forcibly dislodged. The cover 24 is provided with the straps 26 extending along the handle members 17 and 18 and the inner ends of the straps are formed with inturned claws 27 fitting rather loosely within perforations 28 in the handle members. The perforations 28 are arranged at the center of the circle on which the arc of the cover 24 is struck.

15 In the use of the device the blade may be clamped for instance as shown in Figure 1 between the jaws 9 and 10 and the handle gripped with the fingers engaged in the cut out portions 14 and 15. In this manner the 20 device may be pushed across a glass surface for the purpose of removing paint and ink spots, putty and other foreign substances. The blade may be turned at right angles to the position shown in Figure 1 and clamped 25 in the holder to provide a pencil sharpener and knife of general utility. When the nut 12 is loosened the blades will tend to spring apart automatically releasing the blade so that its angular position may be changed or 30 it may be removed or replaced by a fresh blade. The blades may be kept in suitable quantities in the magazine from which they are withdrawn when their use is demanded.

Referring to Figures 4, 5 and 6 the device 35 is generally similar except that the neck portions indicated at 30 between the blade clamps and handle portion are elongated and the cut out parts 31 and 32 are more rectangular with side walls slightly curved.

40 The handle parts indicated at 33 and 34 in this instance are not secured together by any such rivet as rivet 21 shown in Figure 2 but the two portions 33 and 34 meet on the line indicated at 35 in Figure 6, being held normally in this position by the sliding clasp 36 which is also preferably of spring metal and is held in place by reason of its own resiliency aided by the resiliency inherent in the members 33 and 34 which tends to 45 cause these members to extend away from each other. This tendency in the members 33 and 34 of course results from the convergent arrangement of the neck parts 30 and the disposition of the blade clamps.

50 The clamp 36 is in the form of a band with an open side or in the form of a split ring, the ends of which are rounded in order to engage with greater facility the end portion of the handle and the device possesses 55 greater resiliency than if the clasp was an uninterrupted collar.

In this case a magazine is made up by a separate strip 37 of metal riveted as indicated at 38 to one of the handle members 60 and provided at its outer ends with flanges

39 and 40 extending up to the other member. The flanges confine the blades. This device is used precisely in the same way as that heretofore described except that to gain access to the magazine, the clasp 36 is pulled longitudinally off the handle and the two members of the device are then rotated upon the clamped post 11 until the blades may be removed or placed in the holder.

70 Figures 7 and 8 show a still further modified form in which the two members 33 and 34 of the device are spread and rotatable upon the clamp post as just described and in this case a clasp 36 is used also. However, the magazine strip is done away with and replaced by pins 41 and 43 which are riveted to one of the members and adapted to fit in perforations in the other member when the clasp is in place. The blades are fitted 75 between the posts as indicated in Figure 7.

The jaws are slightly concave so as to grip the blades by the edges of the jaws. The holder will take any type of blade and hold it at any angle.

80 The further purpose of the hole 17 is to hang the article upon a hook or other support when not in use.

85 It is obvious that various changes and modifications may be made in the details of construction and design of the above specifically described embodiment of this invention without departing from the spirit thereof, such changes and modifications being restricted only by the scope of the following 90 claims.

95 What is claimed is:—

1. A razor blade holder comprising, a pair of plate spaced apart at one end to provide a handle and being bent toward each other intermediate their ends and reduced in width thereat to provide a finger hold and a pair of spring arms, the other ends of the plates being spaced apart a slight distance to provide jaws and being concave at their inner sides, and a clamping screw secured through the concave portions and arranged to bind against the outer convex sides of the jaws to draw the same toward each other, said jaws being adapted to receive a blade in 10 edgewise relation therebetween, said spring arms and said concave portions of the jaws adapted to cause the gripping of the edge portions of the jaws upon said blade.

11 2. A razor blade holder comprising, a pair of elongated plates diverged and constructed at one end to provide a hollow handle for accommodating a number of razor blades and by means of which the holder may be gripped, means for closing 12 the hollow handle to retain the blades therein, said plates intermediate their ends and beyond the hollow handle being bent toward each other to provide spring portions and extending therefrom in slightly spaced apart 13 relation to the other ends of the plates to

provide a pair of clamping jaws, said jaws being slightly concave from their inner sides to grip a razor blade between the edges of the jaws, and an adjustable clamping member engaging the outer convex sides of said jaws to draw the same together, said jaws being adapted to receive a blade edgewise therebetween and said clamping member adapted for adjustment to bind the jaws on the blade, said spring portions of the plates 10 yieldingly supporting the inner ends of the jaws to insure the uniform gripping of the blade.

DON PARDEE MOON.
